UNITED STATES PATENT OFFICE.

AUGUST SUNDH, OF HASTINGS-UPON-HUDSON, NEW YORK, ASSIGNOR TO OTIS
ELEVATOR COMPANY, A CORPORATION OF NEW JERSEY.

FLUID MOTOR OR PUMP.

1,221,921.

Specification of Letters Patent. Patented Apr. 10, 1917.

Application filed April 19, 1913. Serial No. 762,215.

To all whom it may concern:

Be it known that I, AUGUST SUNDH, a citizen of the United States, residing in Hastings-upon-Hudson, in the county of 5 Westchester and State of New York, have invented a new and useful Improvement in Fluid Motors or Pumps, of which the following is a specification.

My invention relates to improvements in 10 pumps, and particularly such pumps which employ a plurality of reciprocating pistons or plungers adapted to operate with a varying stroke and output.

An object of the invention is the provision 15 of a simple, practical and efficient self contained pump having straight line pistons and cylinders.

A further object of the invention is the provision of a double acting multiple cylinder pump which will operate over a wide range of speed with little or no friction of moving parts.

Other objects of the invention will appear 20 hereinafter, the novel combinations of elements being pointed out in the appended claims.

In the drawings, Figure 1 represents in 25 elevation a pump containing an embodiment of my invention; Fig. 2 is a sectional view of Fig. 1; Fig. 3 is an end section view of Fig. 2 taken on the line 3—3; Fig. 4 is a similar sectional view of Fig. 2 taken on the line 4—4; Fig. 5 is a cross sectional view of Fig. 2 taken on the line 5—5; Figs. 6 and 7 30 are detail views of certain parts shown in Fig. 2; Figs. 8 and 9 are fragmentary side sectional views taken on the lines 8—8 and 9—9, respectively of Fig. 3; Figs. 10, 11 and 12 are diagrammatic views showing the 35 operation of the pistons and valves.

Like reference characters denote similar parts in all of the figures.

Referring to Fig. 1 of the drawings accompanying this specification it will be seen 40 that the pump comprises a cylindrical casing made in two halves or barrels 10 and 11, which are bolted together and provided with bolted-on heads 12 and 13, respectively. A shaft 14 extends through a stuffing box 45 in the casing 11, and through the center of the pump casing and is adapted to rotate in the anti-friction ball bearing 16 carried by the head 12 and the ball bearings 17 carried by the casing 11 (see Fig. 2). The 50 pump comprises a plurality of double acting pistons or plungers such as 18, 19, 20, 21 and

22, which are adapted to reciprocate in cylinders, such as 23 and 24, formed in each half of the casing and arranged in axial alignment with each other. Since these 55 plungers are all alike, and operate in a similar manner, a description of one of them will answer for all. Each of the plungers, such as 18, is flattened in the middle on diametrically opposite sides (see Fig. 7) and to 60 this flattened portion 25 is secured a yoke 26, by means of a pin 27, or other suitable fastening. The yoke 26 is carried by a boss 27 formed in the disk or tilting head 28, and is bushed therein by a removable anti-friction 65 bushing 29, in which the yoke has a small sliding movement. The tilting head 28 is split through the center line of the yoke bushing, and the split parts are fastened together by a number of bolts such as 70 32. The tilting head is supported upon a pair of collars 33, and 34, which loosely surround the shaft 14 and are held in proper position thereon by means of the bearing 75 balls 38 and a hardened steel collar 35. This collar is clamped between a collar 37 turned in the shaft and a sleeve 36, which latter is secured in place by means of a nut 39 (see Fig. 2). The circumference of the collars 80 33 and 34 is turned spherical as is the co-acting inner circumference of the tilting head, so that the latter may be tilted upon the collars without tending to displace the latter from their proper position on the shaft. The right hand end of the tilting 85 head extends outwardly in the form of a circular shell 39, the inner circumference of which carries a hardened steel ball race 40, which is clamped against movement by a securing member or ring 44. A hardened steel 90 collar 42 is arranged concentric with the ball race 40 and a double row of bearing balls such as 41 are placed therebetween. The collar 42 is carried upon and slotted 95 into a wedge 43 which is carried in a slot in the shaft 14, and arranged to have a bodily movement therein in the direction of the axis of the shaft only. As shown in Fig. 5, the wedge is made in two pieces, so that it 100 may be assembled on the shaft, and its shape is such that while it may move longitudinally of the shaft it cannot otherwise be moved. A grooved ring 45 is located at one 105 end of the wedge, and a yoke 47 and pins 46 carried thereon engage the groove in the ring 45, thereby forming a convenient means for effecting a movement of the 110

wedge in the slotted shaft. The yoke 47 is pivoted at 48, and is operatively connected to a traveling nut 49, which latter may be moved in any desired direction by means of a screw 50 and connected hand wheel 51. It will be observed that the ball race 49 is spherical in form, while the ball races formed on the periphery of the collar 42 comprise two parallel grooves, the arrangement being such that the balls will always run true without binding even though the head 28 be tilted through various angles with respect to the shaft. By means of the hand wheel 51, the wedge 43 may be moved 10 along the slot in the shaft and held in adjusted position against any possibility of movement. When the wedge occupies an intermediate position in the slot, the axis of the tilting head coincides with the axis of the shaft and the tilting head assumes the position shown in Fig. 2, with the collar 42 concentric with the shaft. When, however, the wedge is moved in a left hand direction in the shaft slot, the ring or collar 42 is 15 moved out of concentric position and into eccentric position, with respect to the shaft, while the tilting head is tilted in the position shown in Fig. 6. If the wedge be moved to its extreme right hand position, the collar 42 and tilting head will assume the positions shown in Fig. 7, while an intermediate position of the wedge will move the tilting head to a corresponding intermediate position with the axis of the yoke 26 20 lying between the center lines *a* and *b*. If the wedge be in the position shown in Fig. 2 and the axis of the yokes, such as 26, be perpendicular or at right angles to that of the shaft and the latter be revolved, it will be 25 observed that no motion whatever is imparted to the tilting head, and plungers, since the collar 42 is concentric with the axis of the shaft. If the wedge be moved to the extreme left such as is shown in Fig. 6, and 30 the shaft be rotated, the tilting head will oscillate upon the collars 33 and 34, which oscillatory movement will obviously cause all of the plungers to reciprocate in their respective cylinders. The wedge may be 35 adjusted into any desired position with respect to the slot in the shaft, while the shaft is rotating, and in this manner the stroke of the plungers may be varied at will from a maximum stroke to any desired stroke, and by 40 centering the wedge and tilting head, the shaft may continue to rotate without effecting the slightest movement of the plungers.

Referring again to Fig. 2, it will be seen that a web or partition 52 is formed in the 45 casing 10 and this web forms an intermediate bearing for the shaft, which comprises the balls 53 and the co-acting ball races carried upon the shaft and web, respectively. When the tilting head is tilted to one side 50 or the other and the plungers are pumping

against a head or pressure, it is obvious that the head will exert a thrust lengthwise of the shaft. This thrust is transmitted through the bearing balls 38 to the shaft, and the thrust on the shaft is received by 55 the thrust bearings 54 and 55, which bear against the right hand end of the casing 11, and the web or partition 52, respectively. It will be noted that both of these thrust bearings 54 and 55 are self alining, in that 60 one of the faces of the ball races of each bearing is spherical in form and bears against a similar spherical shaped recess in the casing and web, respectively, so that even though the shaft be slightly out of 65 alignment or should it spring a trifle under heavy load, the bearings will perform their proper duty under any and all conditions of speed and load met in practice.

Having described the method of operating 70 the plungers and for varying their stroke, I will now point out the valve apparatus and the method in which the device acts as a pump.

Referring to Figs. 2, 3 and 4, it will be 75 seen that between the cylinders are a plurality of fluid passages such as 56, 57, 58, 59 and 60, which extend completely through both halves, 10 and 11, of the casing, and these passages serve to convey fluid from 80 the cylinders in the casing 11 to the valve apparatus. The right hand head 13 of the casing 11 contains cored ports such as 61, 62, 63, 64 and 65, which connect the right hand cylinders containing the plungers 18, 19, 20, 21 and 22 with the passages 56, 57, 58, 59 and 60, respectively. Each of these 85 passages, such as the lowermost one designated by 58, contains a bushing or lining 66 which forms a fluid-tight passage leading 90 from one end of the casing to the other and the left hand end of each passage is closed by a screw-plug such as 67. Each of the sleeves contains a port such as 69 which is connected by a cored passage such as 68 95 through a port 70 in the hollow plug 71 (see Fig. 2), and by a port, such as 72, to the valve apparatus. The arrangement of the sleeves 66, ports 69, and passages 68 is 100 symmetrical, and the construction is likewise similar in each case. The plugs 71 and ports 70 and 72 associated with the cylinders 24 in the casing 10 are in like manner similar in every respect as also are 105 ports such as 74 which are arranged in each 110 of the cylinders 24.

The rotary valve which controls the flow 115 of fluid to and from the plurality of cylinders will now be described. This valve is located in the cylindrical space between the head 16 of casing 11, and the web 52, and comprises a hub 75 which is rigidly secured to the shaft 14 by means of a key 76 or other suitable fastening means. Spokes 120 such as 77 radiate from this hub, and carry 125

the valve proper, which comprises a cylindrical portion 78 with flanges such as 79 and 80, which are in sliding contact with the sides of the head 12 and web 52, respectively, and are of the same diameter as that of the valve chamber in which they rotate. A flange 81 is located at equal distances from the side flanges 79 and 80, and is of the same diameter as said side flanges. 10 Other flanges such as 82 and 83 are located on either side of the center flange 81, thereby forming four valve chambers, and they are inclined with respect thereto as shown in Fig. 2. These latter flanges are provided 15 with lugs 84, 84, which are for the purpose of insuring a quick opening and closing of the various ports at the proper moment. Two pipes 85 and 87 are located at the top of the casing 10, and one of them, 20 the pipe 85, is connected by a passage or port 86 to the valve chambers located on either side of the center vertical flange 81, while the other, the pipe 87, is connected by a chamber or passage 88, having ports 25 89 and 90 leading into the valve chambers located on the left and right hand sides of the inclined flanges 81 and 83, respectively (see Figs. 8 and 9).

It will be observed that the rotary valve 30 is in effect a double or two-part valve, in that one part controls the fluid passing to and from the cylinders 23, while the other part controls the fluid in a similar manner for the cylinders 24. The passages 56, 57, 35 58, 59 and 60 convey the fluid from the cylinders 23 to the opposite end of the pump casing, and thus the entire valve apparatus may be located at one end of the pump, which arrangement simplifies the valve construction to a large extent, and reduces the tendency for leakage, while at the same time it enables the pump to be much more compact than it otherwise would be and eliminates a complex system of pipe connections 45 as well as reducing the friction of rotating parts to a minimum.

Having pointed out the construction of a pump containing an embodiment of my invention, I will now take up its operation. It 50 has already been shown that by rotating the shaft 14 and connected parts, with the tilting head in tilted position, the plungers will reciprocate in their respective cylinders with a stroke depending on the inclination or 55 amount of tilt of the tilting head, which tilt may be adjusted and controlled between predetermined limits by the hand wheel 51 and maintained constant at any desired degree of tilt.

60 Referring to Fig. 10, wherein the tilting head occupies a neutral position with its axis coinciding with the axis of the shaft, it will be seen that a rotation of the shaft in either direction will merely rotate the valve 65 without in any way effecting a reciprocating

movement of the plungers. If, now, the tilting head be moved or tilted into the position shown in Fig. 11 with the vertical axis *a* of the tilting head inclined with respect to a line *c* drawn perpendicular to the axis of 70 the shaft, or in other words tilted to an angle represented by the angle subtended by the lines *a* and *c*, and the shaft be rotated in a direction so as to bring the parts in the position shown in Fig. 11, the plunger 18 75 moving from right to left, the suction set up in the cylinder 23 by the plunger 18 will cause fluid to flow from the pipe 87 through the valve chamber located between the flanges 79 and 82, through the port 72, hollow plug 71, port 70, passage 56, cored port 81, and into the cylinder 23. The opposite end of the plunger will compress fluid in the cylinder 24, and force it through the port 74, into the valve chamber located between 80 the flanges 81 and 83, through the passage 86, and out of the pipe 85. If the shaft be rotated through 180° and the plunger 18 be moving in the opposite direction as shown in Fig. 12, the fluid flow is reversed, but, 85 since the valve is reversed in position by being rotated a half revolution, the pipe 87 is still a suction or supply pipe while the pipe 85 remains a pressure or discharge pipe. Figs. 11 and 12, clearly show the action of 90 one of the plungers and the valve, and also show how one half of the valve controls the ports 72 leading to the cylinders 23, while the other half of the valve controls the ports 74 leading to the cylinders 24.

100 The action of the other plungers is exactly similar to that of the one just described since the valve and the plungers must operate in synchronism with the rotation of the shaft. That is to say if the valve is arranged so as to take care of one set of cylinders and their plungers such as the cylinders 23 and 24 and plungers 18 of Figs. 11 and 12, when the shaft is revolved one fifth of a revolution or through 72°, the valve will take up the same 105 position with respect to the cylinders adjacent the cylinders 23 and 24 as shown in connection with the latter cylinders, providing the cylinders are of the same number as shown and provided they are symmetrically 110 disposed about the axis of the shaft and arranged at equal distances from each other.

115 The hand wheel 51 may be operated to shift or change the inclination of the tilting head so as to vary the stroke of the plungers 120 and hence vary the output of the pump and by tilting the head in a reverse direction the suction pipe becomes a pressure pipe, and vice versa. This feature is of decided merit where it is desired to maintain the rotation 125 of the shaft at constant speed by a prime mover or motor such as an alternating current motor. The shaft may thus be running continuously in one direction and the pump be made to cease pumping altogether or to 130

pump fluid in either direction and at any desired output by merely manipulating the hand wheel 51.

Any number of cylinders and co-acting 5 pistons or plungers may be used, and I have shown a ten cylinder pump since that arrangement makes a very satisfactory arrangement both as regards the capacity of the pump and as regards the mechanical 10 structure of the same. With a ten cylinder pump at least five cylinders will be compressing, while five are under suction except for the instant when one of the plungers is passing the dead center or having its direction 15 of movement reversed.

The valve is balanced against lateral pressure as an inspection of Figs. 11 and 12 will show, and hence no thrust is placed upon the shaft by reason of the action of the fluid in 20 the valve chambers. The thrust set up in the shaft 14 by the reaction of pressure upon the tilting head is taken up by the bearing balls 38, 38, and the ball bearings 54 and 55, so that little or no friction is induced by a 25 thrust action. In fact the anti-friction bearings throughout the pump are arranged to take care of substantially all friction of moving parts in so far as it is possible or practical so to do. The casing may contain 30 a quantity of oil or other suitable lubricant, which will be distributed by splash to all of the interior working parts of the pump. The entire pump mechanism is inclosed against the possible entry of dirt or foreign matter, 35 and with all parts working in a copious bath of oil the action of the pump in service will be absolutely noiseless and without vibration, since all reciprocating and rotary parts are in perfect balance. The entire pump 40 mechanism is readily accessible for inspection or repair and the only visible moving part in view is the end of the shaft 14.

While the apparatus herein disclosed is particularly adapted for a pump of great 45 power and capacity occupying a minimum amount of space, the same may be used as a fluid pressure motor, and, as such will retain all of the inherent good qualities of the apparatus, the latter being present whether the 50 device be called upon to function as a pump or a motor.

I wish not to be limited to the particular construction herein shown, as various changes in the details of construction and 55 arrangement of parts might obviously be made without departing from the spirit and scope of the invention.

What I claim is new, and desire to have protected by Letters Patent of the United 60 States is:—

1. In a pump, a casing, a shaft adapted

to rotate in said casing, a plurality of cylinders axially and symmetrically disposed about said shaft and in fixed relation to the casing, plungers in the cylinders, a tilting 65 head carried by anti-friction bearings on the shaft, operative connections between said head and plungers, an eccentric associated with said head and shaft and adapted to effect an oscillatory movement of the head 70 upon a rotation of the shaft, and means for varying the eccentricity of said eccentric thereby to vary the length of stroke of the said plungers.

2. In a pump, a casing, a shaft arranged 75 for rotation in the casing, a plurality of cylinders axially and symmetrically disposed about said shaft and in fixed relation to the casing, plungers in the cylinders, a non-rotatable member carried in bearings on the 80 shaft and connected to the plungers, means for effecting an oscillatory movement of said member when the shaft is rotated, and means comprising an adjustable eccentric driven from the shaft for varying the degree 85 of oscillatory movement of said member independently of the shaft to effect a variable length of stroke of said plungers.

3. In a pump, a casing, a shaft arranged 90 to rotate in the casing, a plurality of cylinders axially and symmetrically disposed about said shaft and in fixed relation to the casing, plungers in the cylinders, a tilting head connected to said plungers and adapted to be tilted with respect to said shaft, a 95 wedge associated with said head and shaft for varying the angle of tilt of said head whereby the rotation of the shaft will effect a reciprocation of said plungers by the said head, and means for varying the position of 100 said wedge to control the length of stroke of the plungers.

4. In a pump, a casing, a shaft arranged 105 to rotate in the casing, a plurality of cylinders axially and symmetrically disposed about said shaft and in fixed relation to the casing, plungers in the cylinders, a tilting head having a sliding connection with said plungers and adapted to be tilted with respect to the shaft, a wedge associated with 110 said head and shaft for varying the angle of tilt of said head, and means for changing the position of the wedge to vary the length of stroke of the plungers independently of the shaft.

In testimony whereof, I have signed my name to this specification in the presence of two subscribing witnesses.

AUGUST SUNDH.
